DESIGN FOR ELECTRIC SCISSORS

Robert D. Schoenbrod, Chicago, Ill., assignor to
American Supercraft Corporation, Chicago, Ill.,
a corporation of Illinois

Application October 18, 1940, Serial No. 95,913

Term of patent 7 years

To all whom it may concern:

Be it known that I, Robert D. Schoenbrod, a citizen of the United States of America, residing at 711 West Lake Street, Chicago, Illinois, have invented a new, original, and ornamental Design for Electric Scissors, of which the following is a specification, reference being had to the accompanying drawing, forming a part thereof.

Fig. 1 is a front elevational view; Fig. 2 is a side elevational view; Fig. 3 is a rear elevational view; and Fig. 4 is a top plan view of the electric scissors, showing my new design.

I claim:

The ornamental design for electric scissors, substantially as shown.

ROBERT D. SCHOENBROD.
